DESIGN FOR A PIPE

Herbert R. Maid, Berwyn, Ill.

Application July 25, 1945, Serial No. 120,954

Term of patent 7 years

(Cl. D85—8)

To all whom it may concern:

Be it known that I, Herbert R. Maid, a citizen of the United States, residing in the city of Berwyn, county of Cook and State of Illinois, whose post office address is 4012 Clarence Avenue, Berwyn, Illinois, have invented a new, original, and ornamental Design for a Pipe, of which the following is the specification, reference being had to the accompanying drawing, forming part thereof.

Fig. 1 is a side elevational view of a pipe, showing my new design;

Fig. 2 is a top plan view of the same; and

Fig. 3 is an end elevational view of the same.

I claim:

The ornamental design for a pipe, as shown.

HERBERT R. MAID.
